The ornamental design for a ceiling fan blade, as shown and described.

DESCRIPTION

FIG. 1 is a perspective view of a ceiling fan blade in accordance with my new design, shown in its environment; FIG. 2 is another perspective of the ceiling fan blade in accordance with my design;

FIG. 3 is a rear elevation view of the ceiling fan blade in accordance with my design;

FIG. 4 is a front elevation view of the ceiling fan blade in accordance with my design;

FIG. 5 is a bottom plan view of the ceiling fan blade in accordance with my design;

FIG. 6 is a top plan view of the ceiling fan blade in accordance with my design;

FIG. 7 is a right-side elevation view of the ceiling fan blade in accordance with my design; and,

FIG. 8 is a left-side elevation view of the ceiling fan blade in accordance with my design.

The broken lines showing the environmental structure are for illustrative purposes and form no part of the claimed design.
